UNITED STATES PATENT OFFICE.

NAPOLEON J. PORTLANCE, OF MINNEAPOLIS, MINNESOTA.

FAN-BELT.

1,321,330.

Specification of Letters Patent.

Patented Nov. 11, 1919.

Application filed May 26, 1919. Serial No. 299,810.

To all whom it may concern:

Be it known that I, NAPOLEON J. PORTLANCE, citizen of the United States, residing at Minneapolis, in the county of Hennepin 5 and State of Minnesota, have invented certain new and useful Improvements in Fan-Belts; and I do hereby declare the following to be a full, clear, and exact description of the invention, such as will enable others 10 skilled in the art to which it appertains to make and use the same.

My invention relates to belts generally but is particularly directed to an improved fan belt. Fan belts, as is well known, are generally used in connection with automobiles, 15 for driving the fans.

Generally stated the invention consists of a novel device and combination of devices hereinafter defined and described in the 20 claims.

The belt is made up of a main body of leather or other suitable belting material and a heavy backing of felt. The leather body is provided with several laterally 25 spaced longitudinal rows of perforations that open directly against the felt backing. Between the rows of perforations and on the outer side thereof the leather belt and the felt backing are connected by rows of 30 stitches.

In the accompanying drawings which illustrate the invention like characters indicate like parts throughout the several views.

35 Referring to drawings:

Figure 1 is a plan view of the belt portions thereof being broken away;

Fig. 2 is a side elevation of those portions of the belt shown in Fig. 1;

40 Fig. 3 is a plan view of the belt showing the ends thereof disconnected; and

Fig. 4 is a detailed view in side or edge elevation showing the elements of the belt coupling.

45 The leather body of the belt is indicated by the numeral 5 and the felt backing thereof is indicated by the numeral 6. The numeral 7 indicates the rows of stitches that connects the leather body 5 and felt backing 6.

50 The numeral 8 indicates the perforations in

the leather belt 5. These perforations 8, in the two rows are preferably staggered so that they give a better suction action on the pulleys.

So far as this invention is concerned, the 55 ends of the belt may be connected by any suitable form of coupling, but as shown the coupling comprises two plates 9 and 10. These two plates are riveted or otherwise rigidly secured to the ends of the leather 60 belt 5, and the backing of felt 6 is terminated short of these plates, so that it does not overlap the secured ends thereof. The plates 10 have a T-shaped head 10^a that is engageable with the hook-like over-turned 65 ends 9^a of the plate 9. As stated this belt is especially designed for use as a fan belt. Fan belts, as it is well known, are subject to considerable oil and this oil should be removed from the faces of the pulleys. 70

The perforations in the body of the belt perform two functions to wit; in the first place they give a limited suction on the pulleys which increase the traction of the belt, and in the second place they pick up the oil 75 that gets into the pulleys and carry it to the absorbent felt backing 6. The oil will be absorbed by the backing 6 and finally evaporated and thus will be removed from the working face of the belt and from the pulleys. 80

The absorbent backing 6 is preferably a heavy very closely made felt. However, it might be of other absorbent material capable of performing the function stated. 85

The stitching of the belt, it will be noted, does not interfere with the flexibility thereof but gives the belt increased central strength.

This improved belt has been put into actual use and has been found highly efficient for the purpose it had in view. 90

What I claim is:

1. A belt made up of a body having perforations therein and absorbent backing secured to said body. 95

2. A belt made up of a leather body and a felt backing, said parts being secured together by longitudinal rows of stitches, and said leather body having perforations located between the stitches. 100

3. A belt made up of a leather body and a
felt backing, said parts being secured to-
gether by longitudinal rows of stitches, and
said leather body having perforations lo-
cated between the stitches, the perforations
of the rows being staggered in respect to
each other.

In testimony whereof I affix my signature
in presence of two witnesses.

NAPOLEON J. PORTLANCE.
